UNITED STATES PATENT OFFICE.

WILLIAM F. WILMOTH, OF NEW YORK, N. Y., ASSIGNOR TO NATIONAL BISCUIT COMPANY, A CORPORATION OF NEW JERSEY.

STORAGE AND DISPLAY RECEPTACLE.

Specification of Letters Patent.

Patented Apr. 4, 1916.

1,178,434.

Application filed June 6, 1912. Serial No. 701,992.

To all whom it may concern:

Be it known that I, WILLIAM F. WILMOTH, a citizen of the United States, residing at the city of New York, borough of Manhattan, in the county and State of New York, have invented certain new and useful Improvements in Storage and Display Receptacles, of which the following is a full, clear, and exact specification.

10 My invention relates to improvements in storage and display receptacles, and the same has for its object more particularly to provide a simple, efficient and reliable receptacle, in which the cover portion may be readily attached to, or detached from, the body of the receptacle.

Further, said invention has for its object to provide a receptacle with a transparent cover, and an attaching section whereby the 20 cover may be temporarily yet securely attached to the receptacle without the use of tools or other implements.

Further, said invention has for its object to provide a receptacle with a hinged cover; 25 an attaching section adapted to engage the upper edge or rim of the receptacle, and means for securing said attaching section to said receptacle.

To the attainment of the aforesaid objects 30 and ends my invention consists in the novel details of construction, and in the combination, connection and arrangement of parts hereinafter more fully described and then pointed out in the claims.

35 In the accompanying drawings, forming part of the specification, wherein like numerals of reference indicate like parts, Figure 1 is a perspective view showing one form of receptacle constructed according to, and embodying my said invention; Fig. 2 is a central vertical section showing the cover closed, in full lines, and folded back in broken lines; Fig. 3 is a detail perspective view, one end of the attaching section showing the securing means adjusted in position 45 to secure the cover to a receptacle, and in broken lines, adjusted to position preparatory to attaching to or removing from a receptacle; Fig. 4 is an enlarged detail 50 transverse section showing the cover attached to the receptacle, and in its closed position; Fig. 5 is a similar view showing the cover folded fully back; Fig. 6 is an enlarged detail plan or top view showing a 55 portion of a receptacle with the cover in

position and opened at right angles to the top of the receptacle, and Fig. 7 is an enlarged detail rear view of the upper part of a receptacle, with the cover in closed position thereon.

60 In said drawings 10 denotes a sheet metal receptacle or can of the type commonly used for the packing and shipment of crackers or biscuits. Along the upper edge of said receptacle 10 is provided an inwardly projecting flange 11 which extends entirely around the same. The said flange 11 has its inner portion 12 doubled upon itself for the purpose of reinforcing the same.

65 13 denotes a detachable cover comprising 70 a transparent section 14, and an attaching and securing section 15. The transparent section 14 consists of a frame section 16 having a depending flange extending along two of its sides and its front. Within said 75 frame section 16 is secured a transparent plate or glass 17 which is secured in position therein by clips or retaining ears 18, 18, and along the rear edge of said frame section 16 are provided a pair of hinge members 80 19, 19.

75 The attaching and securing section 15 is formed of a relatively narrow strip of sheet metal 20 having its inner edge 21 bent downwardly and outwardly, and its extreme edge 85 folded back upon itself. At the opposite ends of said strip 20 are provided rearwardly projecting securing ears 22, 22. The said ears 22, 22 are formed integral with the upper portion of the strip 20, and have their 90 inner edges partly cut away at 23, 23 in order to permit of the inner edge 21 of said strip engaging properly with the portion of the flange 11 along the rear top edge of the can, and the inner portions of the ears 22, 95 22 to rest upon the top of said flange 11, adjacent to the rear corners of the receptacle or can. Along the outer edge of the upper portion of the strip 20 are provided a plurality of hinge members 24, 24, 24, which 100 are adapted to fit intermediate the hinge members 19, 19 of the cover, and be operatively connected thereto by a hinge pin 25.

105 To attach and secure the cover 13 to the receptacle or can 10, it merely becomes necessary to slip the folded inner edge 21 of the attaching section 15 over the edge of the portion of the flange 11 provided at the upper rear edge of the receptacle or can 10. As the portion 21 of the attaching section 110

20 is more or less yielding, it will engage frictionally with said flange 11 and form a tight joint. As soon as the attaching section 15 is properly adjusted in position upon 5 said flange 11, the ends of the ears 22, 22, which project rearwardly between the top of the can or receptacle, and the hinged edge of the cover 13, are bent downwardly, as shown at Figs. 1 and 3, against the rear side 10 of the receptacle or can, and hold said attaching section 15, and cover 13 carried thereby firmly in position upon the can or receptacle. To remove the cover 13, it merely becomes necessary to restore the ends 15 of the ears 22, 22 to their horizontal positions, as indicated in broken lines at Fig. 3, and then withdraw the attaching section 15 from the flange 11.

It is to be noted that a particular advantage which is obtained by the use of my invention is that it enables the manufacturer 20 of the article packed in the receptacle or can to provide the can or receptacle with a simple, inexpensive cardboard, metal or wooden 25 cover which may be readily applied to the can or receptacle to protect the contents during shipment or storage previous to displaying the same for sale, and that by supplying the retailer with a number of detachable 30 covers, as herein shown and described, it merely requires the retailer to remove the shipping cover, and apply a detachable cover which may remain upon the receptacle or can until the same is emptied, whereupon 35 said cover may be easily detached and transferred to a new can. By this means the number of glass covers used by the manufacturer of the goods packed in the cans may be greatly reduced, and at the same 40 time the breakage incident to shipment entirely obviated. Further, it is to be noted that by means of my invention I am enabled to provide a can with a cover which is so constructed that the same may be folded 45 to a vertical position flat against the rear side of the can without danger of straining said cover, the hinge or connected parts.

Having thus described my invention, what I claim and desire to secure by Letters Patent is:

1. The combination with a receptacle having a laterally extending flange at its open end, of a longitudinally-grooved plate adapted to engage with said flange, foldable members at the opposite ends of said plate 55 adapted to be folded into engagement with the side of said receptacle from which said flange extends for securing said plate to said receptacle, and a hinged cover pivotally secured to said plate, substantially as specified. 60

2. The combination with a receptacle having a flange extending laterally from its open end, of a longitudinal plate provided along one of its longitudinal edges with a 65 groove adapted to engage said flange, foldable projections extending transversely from the opposite longitudinal edge of said plate for securing said plate to said receptacle, and a cover pivotally secured to said plate, 70 substantially as specified.

3. The combination with a receptacle having an inwardly projecting flange at its open end, of an attaching plate having one of its longitudinal edges bent downward 75 and inward and adapted to receive said inwardly projecting flange, foldable projections extending from opposite edges of said attaching plate and adapted to be folded over the open end of said receptacle, and a 80 cover pivotally secured to said attaching plate, substantially as specified.

4. The combination with a receptacle having an inwardly extending flange at its open end, of a detachable cover comprising an attaching plate having one of its longitudinal edges folded over parallel therewith, foldable projections extending transversely from the opposite ends of said attaching plate, and a cover part pivotally secured to said attaching plate intermediate said foldable projections, substantially as specified. 85

Signed at the city of New York, in the county and State of New York, this sixth day of May, nineteen hundred and twelve. 90 95

WILLIAM F. WILMOTH.
